SCREW HOLDING SCREW DRIVER

Bennie J. Johnson, Bridgeport, Conn.

Application April 26, 1946, Serial No. 665,123

5 Claims. (Cl. 145—50)

1

This invention relates to screw drivers.

An object of the invention is to provide an improved screw driver having simple and economical-to-manufacture retaining means for holding a screw on the bit prior to insertion of the screw.

A feature of the invention is the provision of a screw-retaining means which may be swung to and resiliently held in an inoperative position when it is desired to use the screw driver without the said means being operative.

Another feature of the invention is the provision of a screw driver and screw-retaining means in which the latter may be adjusted to vary the tension or pressure by which the screw is held on the bit.

Other features and advantages will herein-after appear.

In the accompanying drawings:

Fig. 1 is a side elevation of the improved screw driver of the present invention, with the screw-retaining means in extended or operative position.

Fig. 2 is a fragmentary side elevation showing the bit portion of the screw driver, and showing a screw being held in place prior to insertion.

Fig. 3 is a longitudinal section through the bit portion of the screw driver.

Fig. 4 is a fragmentary broadside view of the bit and screw-retaining means of the screw driver.

Fig. 5 is a fragmentary side elevation showing the bit portion of the screw driver, and showing the screw-retaining means shifted to retracted or inoperative position.

Fig. 6 is a fragmentary longitudinal section through the bit portion of a screw driver illustrating a modification of the invention, and

Fig. 7 is an enlarged fragmentary view of the tip portion of the screw driver of Fig. 1.

As shown, the improved screw driver of the present invention comprises a shank 10 having at one end a handle 11 and at the other end a flat-tapered bit portion 12. A resilient blade or flat spring 13 is secured to the bit portion 12 of the screw driver, the said spring being preferably of spring steel and having intermediate its ends an aperture for receiving a screw 14 which is threaded into the bit portion 12 and is locked therein by a lock nut 15.

The flat spring 13 has adjacent its forward end 16 a curved portion 17 which extends toward the flat surface 18 of the bit portion 12 and engages the latter. The other end 19 of the spring 13 is bent so as to also engage the bit portion 12 of

2

the screw driver, but on the opposite side of the screw 14.

Thus the curved portion 17 and the curved end 19 of the spring operate to provide a space 20 between the intermediate part of the spring and face 18 of the bit portion.

For the purpose of yieldably holding the spring 13 in the operative position shown in Figs. 1 and 2, the end 19 thereof is made pointed (Fig. 4), and a small straight-walled bore 21 is provided in the face 18 of the bit portion to receive the said pointed end. A detent is thus formed by engagement of the end 19 with the bore or recess 21, and preferably the edge of the said recess 21 is not beveled but is made sharp so that it tends to bite into the end 19.

The flat spring 13 is supported in its operative position shown in Fig. 1 under a slight tension, as imposed by the screw 14. While this tension does not have any considerable magnitude it is sufficient, in conjunction with the sharp edges of the recess 21, to require that a fairly substantial pressure be exerted on the spring to swing or swivel the latter about the screw 14. By this organization, therefore, the spring 13 will be securely held against accidental dislodgement from its operative position under normal conditions of use.

Preferably the end 16 of the flat spring 13 is made to extend or project slightly beyond the extreme tip 12a of the shank portion 12, as shown in Figs. 1 and 2, and the said tip is slabbed at 22 to reduce its thickness slightly.

In operation, the screw driver of this invention is applied to the slotted head of a screw such as that shown at 23, Fig. 2, by first engaging the end 16 of the spring with the face 23a of the screwhead and then shifting the screw driver shank 10 so as to cause the said end to partially enter the slot of the head, the slabbed tip 12a of the bit portion not, however, immediately entering the slot due to a space 20a existing between the tip 12a and the spring end 16. The screw driver shank 10 is then shifted laterally to cause lateral pressure on the end 16 of the spring, flexing the latter and reducing the amount of the space 20a, whereupon it will be found that the slabbed tip 12a of the bit portion is brought in position to fully enter the slot of the screwhead. During this latter operation the flexure of the spring 13 takes place mainly in the curved portion 17 thereof.

In applying the screw driver to a screw in the manner described above, the operation is facilitated if the tip 12a has a bevel 12b, as shown in

Fig. 7, to enable the tip portion to easily slide over the head of the screw without cutting into the latter.

The slabbed tip 12a of the screw driver and the end 16 of the spring when extending into the slot of the screwhead will exert a substantial outward pressure on the walls of the slot, and will securely retain the screw on the bit portion 12 of the driver.

It will be noted that, due to the novel shape of the spring 13, tightening of the screw 14 will cause a decrease in the space 20 between the spring and the shank portion 12, and an increase in the space 20a, and this is an important feature of the invention since it enables the gripping force of the tip 12a, and end 16 of the spring to be varied to suit different conditions of use and different sizes of screws.

Where large screws are to be handled, the pivot screw 14 may be driven further into the bit portion 12 so as to increase the separation or space 20a, and where small screws are to be handled, the pivot screw 14 may be unscrewed slightly, decreasing the space 20a. It will be understood that the gripping force exerted by the end 16 of the spring 13 generally varies directly with the spacing 20a between the said end and the tip 12a of the bit portion 12. After each adjustment of the pivot screw 14 the lock nut 15 is again tightened so as to securely hold the screw in its newly adjusted position.

If it should be desired to use the screw driver without utilizing the retaining action of the spring 13, the latter may be pivoted about the screw 14 and shifted to an inoperative position as shown in Fig. 5. For the purpose of yieldably holding the spring 13 in the said inoperative position the bit portion 12 of the screw driver is provided with a second detent recess 24, adapted to receive the pointed end 19 of the spring.

A modification of the invention is illustrated in Fig. 6. The bit portion 25 illustrated therein has a pivot screw 26 threaded into the said portion and locked by a lock nut 27. Carried under the head of the screw 26 is a flat spring 28 having an elongate slot 29 through which the screw extends, and having a curved portion 30 adjacent its forward end 31, the opposite end 32 of the spring being also curved inward, toward the shank portion 25. The said shank portion has a slot 33 in one face to receive the end 32 of the flat spring, and to prevent the latter from having pivotal movement about the screw 26.

In Fig. 6, the spring 28 is shown in extended or operative position, and the retracted or inoperative position is shown by dotted lines. It will be understood that, by the provision of the slot 29 in the spring and the slot 33 in the shank portion 25 of the screw driver, the spring 28 is shiftable longitudinally between its extended and retracted positions.

If desired, a pair of recesses 34 may be provided in the bottom of the slot 33 to accommodate the tip portion of the spring 28, the said portion being then made pointed. By this arrangement the spring 28 will be positively locked in either the extended or the retracted position.

As in the first described embodiment of the invention, the spring 28 is adjustable to vary the gripping force exerted in the slot of a screwhead, this being accomplished by turning the screw 26 either in or out.

Variations and modifications may be made within the scope of this invention and portions

of the improvements may be used without others.

I claim:

1. A screw driver having a spring arm overlying its bit portion with an intermediate portion and end portion thereof in spaced relation to the bit portion, the tip of the bit portion and the spaced end of the arm being juxtaposed and insertable in the slot of a screw to grip the latter and retain it on the bit portion; and adjustable means carried by the bit and passing through the intermediate spaced part of the arm for securing the arm to the bit and for varying the gripping force exerted by the tip of the bit portion and the end of the arm on the screw slot, the said arm being pivotally movable on the bit portion to swing the end of the arm either adjacent the tip of the bit portion for engagement with a screw, or away from the said tip to an inoperative non-screw engaging position.

2. In a screw driver, a spring arm pivotally secured, at a point substantially midway between its ends, to the bit of the screw driver, one end and an intermediate portion of the said arm being bent laterally and engaging the said bit, the other end of the arm and the part intermediate the said bends being thereby spaced from the bit and the said other arm end and bit being juxtaposed and insertable in the slot of a screw to grip and retain the latter, the pivot for the arm passing through the intermediate portion and being adjustable to vary the spacing between the bit and said intermediate portion and the said other end of the arm, thereby to adjust the gripping force of the said bit and arm end on the screw; and means including a recess on the bit and a projection on the arm, entering the said recess, for yieldably holding the arm in operative position, the said arm when pivotally moved displacing the said projection from the said recess and separating and disassociating the screw-engaging end of the arm from the screw-engaging portion of the bit.

3. A screw driver having a spring arm secured to its bit, one end and on intermediate portion of the said arm being bent laterally and engaging the said bit, the other end of the arm and the part intermediate the said bends being thereby spaced from the bit and the said other arm end and bit being juxtaposed and insertable in the slot of a screw to grip and retain the latter; means carried by the bit and passing through an opening in the part of the arm intermediate said bends and securing the latter to the bit, for varying the spacing between the bit and the said other end of the arm, thereby to adjust the gripping force of the said bit and arm end on the screw; said opening in the arm extending longitudinally and enabling the arm to have longitudinal movement on the bit between an extended operative position, and a retracted inoperative position wherein the screw-engaging end of the arm is separated and disassociated from the screw-engaging part of the bit; and means including a slot in the bit and a portion on the bit-engaging end of the arm entering the said slot, for guiding the arm to either operative or inoperative position and means in the slot cooperating with said end for holding the arm against shifting when in the said positions.

4. A screw driver having a spring arm overlying its bit portion with one end portion and intermediate portion of said arm in spaced relation therewith, the tip of the bit portion and said one end of the arm being juxtaposed and insertable in the slot of a screw to grip the lat-

ter and retain it on the bit portion; and adjustable screw means carried by the bit and passing through the intermediate portion of the arm for securing the arm to the bit and varying the spacing between the bit portion and the spaced end of the spring arm for increasing or decreasing the gripping force exerted on the screw by the said tip of the bit portion and end of the arm.

5. In a screw driver, a spring arm, pivot means securing said arm, at a point substantially midway between its ends, to the bit of the screw driver, one end and an intermediate portion of the said arm on opposite sides of said pivot means being bent laterally and engaging the said bit, the other end of the arm and the part of the arm intermediate the said bend and first end of the arm being thereby spaced from the bit with the other end of said arm and the end of the bit being juxtaposed and insertable in the slot of a screw to grip and retain the latter; and means including a recess in the bit and a projection on the arm, entering the said recess, for

yieldably holding the arm in operative position, the said arm when pivotally moved displacing the said projection from the said recess and separating and disassociating the screw-engaging end of the arm from the screw-engaging portion of the bit, the pivot means for the arm passing through the spaced part intermediate the bends so that the arm is relieved of frictional engagement and moves freely about the pivot when the bit engaging portions of the arm are moved out of engagement with the bit.
